UNITED STATES PATENT OFFICE

SIMON E. SCHROEDER, OF NEWTON, IOWA, ASSIGNOR, BY MESNE ASSIGNMENTS, TO
AUTOMATIC WASHER COMPANY, OF NEWTON, IOWA, A CORPORATION OF DELA-
WARE

WRINGER

Application filed March 8, 1928. Serial No. 259,984.

This invention relates to wringers for washing machines.

One of the objects of the invention is in the provision of a safety wringer for washing machines.

Another object is in the provision of a wringer for washing machines, the same being of a safety type and including a moving belt portion co-operating with the roll members in such manner that the clothes content may be placed upon the belt portion and carried between the rollers without the necessity of the operator forcing the clothes content between the rolls.

Still another object lies in the provision of a safety wringer mechanism including pressure rolls and a belt portion, the upper end of said pressure roll being fashioned for movement from one side of the pressure roll to the other.

A further object lies in the provision of a safety wringer mechanism wherein there is a power roll, a belt member cooperating with the power roll upon which the clothes content is adapted to be placed prior to the wringing action, and a pressure roll normally disposed laterally of the power roll but adapted for movement to a position on the opposite side of the power roll to permit the operator to accomplish a reverse wringing operation.

Other objects will appear in the following specification taken in connection with the annexed drawings, in which—

Fig. 1 is a plan view from above of the safety wringer; and

Fig. 2 is an end elevation thereof.

Before referring specifically to the drawings, it might be said that there is considerable development work in the washing machine industry tending towards safer wringer mechanism. The well known wringer is undoubtedly very efficient as far as the wringing operation is concerned. However, when one considers that so many devices have been provided for relieving the pressure between the rolls when the operator has her finger, hand or arm caught in the wringer, it is apparent that accidents do happen to wringers and that any device which goes further than

the safety release mechanism merits consideration.

The present applicant has been active in the development of washing machines and wringer mechanism for a considerable period 55 of years and has been active throughout that period in the designing of washing machines, wringer mechanism and practically every element in connection with same. He recognizes the necessity of devising some wringer mechanism which will obviate accidents.

He presents in this instance his idea of a safety wringer mechanism which goes further than the ordinary safety release for the pressure roll, in that it is contemplated that 65 the operator merely place the clothes content to be wrung upon a moving belt or platform portion, which in turn carries the clothes content between the rolls. There is no necessity in this type of wringer for the 70 operator to force the clothes into the bite of the rolls, which obviously causes practically all of the accidents to women, who, it must be admitted, are in practically every instance, the operators of washing machines and 75 wringing devices thereon.

In the drawings, applicant has disclosed a simple wringer device which as far as structural make-up is concerned, would not materially change the appearance of a washing 80 machine, and as a matter of fact, due to its low height, would probably enhance the general appearance, besides creating a much more efficient wringer, as far as the safety element is concerned, and there is no question 85 but that the general public is at this date much concerned with this feature of safety.

Applicant provides a wringer frame comprising end pieces 10 and 11 and a bottom plate 12 acting as a guide for a driven belt 90 member and connecting the said end pieces. This bottom plate has its edge portions curved as at 13 and 14 and also cut away in the plural manner shown at 15, for the purpose of carrying the plural belt members 95 later to be described.

Cross bars 16 and 17 project between the side plates at each side of the wringer in a manner to support the wringer, as well as the end portions which operate also as catch 100

members for the pressure roll. A power roll 18 is disposed in the wringer frame, the same having the power shaft 19 disposed centrally thereof and projecting through the side plate 11 in a manner to be connected to the driving means for the wringer and being so conventional as to obviate the necessity of description.

The power shaft 19 is carried in bearing members 20 and 21, which in turn are carried in supporting brackets 22 and 23 formed either as a part of the end plates or secured thereto in any manner desired. A plurality of strips or belts 24 surround the power roll and the bottom plate 12 of the wringer frame, said belts being guided by the cut-away portions 15 previously described, and passing smoothly about curved portions 13 and 14 of the plate 12. Obviously, these plural strips, which actually make up one belt member, may rotate in either direction, the same being controlled by movement of the power roll. A pressure roll is shown at 25, the shaft 26 thereof having its end portions carried in plural bearings 27 slidably mounted in the stamped metal pressure roll framing member 28. This pressure roll frame not only carries the coil tension springs 29 for the pressure roll, which normally tends to force same against the power roll, but also said frame is adapted to rotate upon the previously described stamped metal brackets 22 and 23, which support the bearing for the shaft 19 of the power roll. In other words, the framing for the pressure roll may be moved at will from one side or the other of the power roll.

Set screws 36 and block 37 have been provided for adjusting the tension of coil springs 29 used to apply pressure of roll 25 against power roll 18. A pin 38 is also provided to act as a stop for bearing 27 when tension is released from pressure against the power roll.

Means for moving the pressure roll from one side to the other of the power roll to accomplish reverse wringing operation, is provided in the manually controllable lever 30, the same comprising handle portion 31, the portions 32 of which lie flat against the upper side of the frame for the pressure roll, said portions being carried in a rotatable manner by clips 33 upwardly projecting therefrom and formed as a part of the framing member, the outer ends 34 of the bar 30 being offset in such manner as to be capable of movement within the latch portions 35 formed in the ends 10 and 11 of the wringer frame, and when in this position operating to hold the wringer frame for the pressure roll in a fixed position as respects the power roll. It is apparent also that when said bar 30 is moved to a position to hold the pressure roll in one of its lateral positions, tension will be applied between the pressure roll and power roll, due to the sliding connection between

the frame for the pressure roll and the bearings for the power roll.

As far as the operation of the present wringer is concerned, the actual wringing operation is accomplished by the movement of the clothes content between the power and pressure rolls, just as in any of the well known wringer devices. However, the movement of the power roll transmits similar movement to the belt member, made up of the plural strips, and the operator may in this instance place the clothes upon this movable belt, which in turn carries the clothes content between the rolls and obviates the necessity of forcing the clothes into the bite of the rolls. This device also operates to prevent the clothes from continuing around the pressure roll and becoming entangled thereabout. This is obvious, in view of the fact that the clothes will normally tend to follow the movement of the belt, thus overcoming another of the disadvantages of the ordinary wringer.

As far as the movement of the pressure roll from one side to the other to accomplish the reverse wringing operation, which is necessary when one considers that wringers are swung about from one position to another to take care of the various wash and rinse tubs about the washer, the operator has merely to move the handle 31 to release the ends 34 from the latch portions 35 and thereupon swing the entire pressure roll and framing portion to an opposite position, thereupon latching same in exactly the same manner.

It is apparent that the present safety wringer has also the advantage of any of the well known safety devices, inasmuch as same has a safety release means for the pressure roll, it being apparent that in case the operator should have her finger or hand caught between the rolls,—although such a condition could hardly be possible with the present wringer—nevertheless, even in such instance, all that the operator would need to do would be to move handle 31 to release position, which would automatically release the pressure between the rolls.

What I claim is:

1. In a wringer device the combination of a wringer frame, a power roll, a pressure roll, means for latching the pressure roll in operative position on either side of the power roll, said positions being substantially symmetrical with respect to a vertical plane through the horizontal axis of the power roll, a guide member spaced from and below the power roll and projecting laterally an equal distance beyond each side of a vertical plane in which the axis of the power roll lies, and a belt member driven by said power roll and passing about the guide member, said belt member cooperating with the roll members to carry the clothes content into the bite of the rolls when

115

125

130

the pressure roll is in operative position on either side of the power roll.

2. In a wringer device, a power roll, a pressure roll shiftable from one operative position in pressure relation with the power roll to a second operative position in pressure relation with the power roll, belt guiding means spaced from the power roll, a belt trained about the power roll and the belt guiding means, said guiding means extending on opposite sides of, perpendicular to, and equal distances from, a plane in which the axis of the power roll lies, said plane bisecting the angle formed by two planes formed by passing through the axis of the power roll and the axes of the pressure roll in both of its operative positions.

In testimony whereof I have hereunto affixed my signature.
